UNITED STATES PATENT OFFICE.

FRANK H. LINDNER, OF BAYONNE, NEW JERSEY.

OSCILLATING-PISTON ENGINE.

SPECIFICATION forming part of Letters Patent No. 756,664, dated April 5, 1904.

Application filed January 17, 1902. Serial No. 90,205. (No model.)

To all whom it may concern:

Be it known that I, FRANK H. LINDNER, a citizen of the United States, and a resident of Bayonne, county of Hudson, and State of New Jersey, have invented certain new and useful Improvements in Oscillating-Piston Engines, of which the following is a specification, reference being had to the accompanying drawings, forming a part thereof, in which similar letters of reference indicate corresponding parts.

My invention relates to a new and improved form of oscillating-piston engine wherein I arrange the oscillating pistons within a casing 15 at points equidistant from a driving-shaft mounted upon and passing through the casing and connect the said oscillating pistons to the driving-shaft by a particular arrangement of gears mounted upon the shafts of the oscillating and auxiliary shafts and segmental gears mounted upon and securely fastened to the said driving-shaft.

The important feature of my invention is the particular arrangement of the gears and 25 segmental gears operating in conjunction with secondary and auxiliary gears to give the driving-shaft a continuous rotary motion.

A further feature of my invention is the projecting arms, which I shall hereinafter designate as "cam-arms" and which are formed 30 upon or attached to the gears and segmental gears. These cam projections engage with one another and have an important function in the operation of my engine, as will be hereinafter fully described.

My invention consists, essentially, of the pistons inclosed and oscillating within their respective compartments. When steam or any suitable expansible fluid is introduced behind 40 the pistons, the said pistons will oscillate and act to give an oscillating motion to the main gear-wheels which are attached to the shafts, which in turn are fastened to and extend outwardly from the said oscillating pistons.

45 These gear-wheels, by means of secondary gear-wheels, in turn give an oscillating motion to a series of gear-wheels which I shall hereinafter designate as "auxiliary" gear-wheels. The main gear-wheels engage consecutively with one of the segmental gears

upon the aforesaid driving-shaft and act to rotate the shaft while the pistons move in a direction opposite to the rotation of the said driving-shaft. When the pistons move in the direction corresponding to the direction 55 of the rotation of the driving-shaft, the aforesaid auxiliary gear-wheels, operating in conjunction with the said secondary gear-wheels, engage with a second segmental gear, which is securely fastened to the driving-shaft, and 60 act to give the shaft a rotary motion in the same direction as that imparted by the main gears.

The secondary segmental gear hereinbefore mentioned I shall hereinafter designate as the 65 "auxiliary segmental gear."

The object of my invention is to provide an engine of the character described wherein I can use the expansive element of the fluid employed to its fullest extent and give to the 70 driving-shaft a uniform, even, and continuous rotary motion.

A further object is to provide an engine of the character described constructed and operating so that at no time during the rotation 75 of the driving-shaft are all of the pistons in action, two of the pistons always receiving the full impact of the expansible fluid used, giving thereby to the driving-shaft a continuous and even rotary motion.

80 A further object of my invention is to provide an engine of the nature above described which shall embody compactness and simplicity in construction, economy in cost of manufacture, and other novel features, which will 85 hereinafter be fully described and explained.

In the drawings I have illustrated an engine particularly designed for use as a steam-engine, and to facilitate my description I shall confine myself hereinafter to a steam-engine; 90 but it is obvious that by slight modifications I may adapt my engine so that I may use gas or any other suitable fluid.

I attain my objects by the mechanism illustrated in the accompanying drawings, in 95 which

Figure 1 is a top view of my engine. Fig. 2 is a cross-section taken through the center of the pistons and piston-chambers looking in the direction indicated by the arrow α in Fig. 100

1. Fig. 3 is a sectional view taken on the line 2 2 of Fig. 1 looking in the same direction. Fig. 4 is a sectional view taken on the line 3 3 of Fig. 1 looking in the same direction. Fig. 5 5 is a sectional view taken on the line 4 4 of Fig. 1 looking in the same direction. Fig. 6 is a section through the line 1 1 looking in the direction indicated by the arrow X, Fig. 1, and shows the inner flange of the cam-wheel removed. Figs. 7, 8, and 9 are detail views of the valves shown partly in section, and Fig. 10 is a view of the cam-wheel shown partly broken away.

Referring to Figs. 2, 3, 4, and 5 of the drawings, A, B, and C designate the oscillating pistons, having projecting vanes and inclosed within the shell or casing S, which is formed with a separate compartment for each piston.

S' designates a driven shaft which is rotatably mounted upon and extends through the casing at a point equidistant from the center of the pistons A, B, and C.

Within the piston-compartment I form the abutments a', b', and c', against which the peripheries of the pistons A, B, and C, respectively, are adapted to engage.

Extending outwardly from and concentric with the pistons A, B, and C are the shafts a², b², and c², whose outer ends are mounted in 30 the plate P and to which the main gear-wheels A', B', and C', respectively, are fastened. Each of the said main gear-wheels is adapted to engage consecutively with the segmental gear T, while the pistons move in a direction opposite to the direction of the rotation of the driving-shaft S'. The said segmental gear T is securely fastened upon the said driving-shaft. Secondary gear-wheels A'', B'', and C'' are securely fastened upon the shafts a², b², 40 and c², respectively, near their outer ends and engage with the secondary gear-wheels E, F, and G, which are securely mounted upon the auxiliary shafts e, f, and g, respectively. The auxiliary gear-wheels E', F', and G' are also 45 mounted upon the auxiliary shafts e, f, and g, respectively, and engage consecutively with the auxiliary segmental gear T', while the pistons move in a direction corresponding to the direction of the rotation of the driven 50 shaft to which the auxiliary segmental gear is attached.

The abutments a', b', and c' are provided with two openings or ports each, 1^a and 2^a, 1^b and 2^b, and 1^c and 2^c, respectively, which 55 open into the piston-chambers on each side of the abutments.

The piston-chambers are connected, by means of pipes and valves, to the source of steam-supply and exhaust-openings in the following order: The ports 1^a and 2^a, leading into the chambers of the piston A, are connected to the valve-boxes 1^A and 2^A, respectively, by means of the connecting-pipes 3^a and 4^a. The ports 1^b and 2^b, leading into the chambers of 65 the piston B, are connected to the valve-boxes

1^B and 2^B, respectively, by means of the connecting-pipes 3^b and 4^b, and the ports 1^c and 2^c, leading into the chambers of the piston C, are connected to the valve-boxes 1^C and 2^C, respectively, by means of the connecting-pipes 70 3^c and 4^c.

The admission and exhaust of the steam into and out of the chambers of the piston-compartments are governed by means of the rotary valves V, Figs. 7, 8, and 9, having a passage 75 or cut-out portion v and inclosed within each of the valve-boxes.

The pipes 9^a, 9^b, and 9^c are steam-supply pipes, which will when connected, by means of the passages v, Figs. 7, 8, and 9, to the 80 ports leading into the piston-chamber supply steam to drive the piston. When the passages v connect the ports leading into the piston-chambers with the exhaust-ports, the steam within the chambers is allowed to exhaust out 85 through the pipes O.

In Figs. 7, 8, and 9 I show the valve-boxes in section to better illustrate their interiors, and I show the connected arms with their roller ends in front of the sections to better 90 show their relative positions.

The valves V are actuated at the proper time to admit and exhaust steam into and out of the piston-chambers by means of cams formed upon the flanges W' and W² upon the 95 cam-wheel W, which are adapted to engage with the roller ends of the projecting arms securely fastened to the ends of the shafts of the rotary valves V. The valves within the valve-boxes 2^A, 2^B, and 2^C are provided with 100 the short shafts v², v³, and v⁴, respectively, to the ends of which are fastened projecting arms integrally connected and provided with roller ends adapted to engage with the cam formations upon the flanges of the cam-wheel 105 W. The projecting arms upon the shafts v², v³, and v⁴ are provided with the rollers r, r', r'', and r³. The valves operating within the valve-boxes 1^A, 1^B, and 1^C are provided with the long shafts 1^v, 2^v, and 3^v, respectively, to 110 the ends of which are fastened projecting arms integrally connected, which have mounted upon them the rollers 1^r, 2^r, 3^r, and 4^r, similar to those of the projecting arms of the short shafts and adapted to engage with the cam 115 projections upon the flanges of the cam-wheel W to operate the valves. Cam projections w, w', w² and w³ are formed upon the flange W' of the cam-wheel, and the cam projections 1^w, 2^w, 3^w, and 4^w are formed upon the flange W², and in Fig. 3 I have shown the relative position of the last-mentioned cam projection by dotted lines. The cam projections are adapted to engage with the rollers at the proper time to operate the valves, as will be herein-after described.

The steam-supply pipes 9^a, 9^b, and 9^c are connected to and lead from one main supply-pipe, which may be provided with a suitable valve and controlled by any approved governor at- 130

tachment, and the exhaust-pipes O may all lead into one general exhaust-pipe to carry off the exhaust-steam.

Referring again to the gear-wheel mechanism, t designates a cam-arm formed upon the segmental gear T and adapted to engage consecutively with the cam-arms 1^a , 1^b , and 1^c , formed upon each of the main gear-wheels A', B', and C, respectively, just before the teeth of the said segmental gear are about to engage with the teeth of each main gear-wheel and before steam is allowed to enter the piston-chamber to drive the piston. Upon the auxiliary segmental gear T', I form a similar cam-arm t^s , which is adapted to engage with the cam-arms 1^e , 1^f , and 1^g , formed upon each of the auxiliary gears E', F', and G', respectively, just before the teeth of the said auxiliary segmental gear T' are about to engage with the teeth of each auxiliary gear-wheel and before steam is allowed to enter the piston-chamber to drive the piston in the opposite direction. The segmental gear T is further provided with a second cam-arm t^s , which engages consecutively with the cam-arms 2^a , 2^b , and 2^c , formed upon the main gear-wheels A', B', and C', respectively, just before the teeth of the said segmental gear T disengage the teeth of each of the said main gear-wheels and act to continue the movement of each piston until its vane reaches the abutment. The auxiliary segmental gear is also provided with a second cam-arm t^s , similar to the cam-arm t^s , which is adapted to engage consecutively with the cam-arms 2^e , 2^f , and 2^g , formed upon the auxiliary gear-wheels E', F', and G', respectively, just before the teeth of the auxiliary segmental gear T' disengage the teeth of the said auxiliary gear-wheels and act to continue the movement of each piston in the opposite direction until its vane reaches the abutment.

The filled-in sections P and P' in Fig. 2 denote chambers containing live or active steam.

In practice my device operates as follows: Referring to Fig. 2, I will assume that the engine is in full operation and that the main shaft S' is rotating in the direction indicated by the arrow X^2 . The pistons A and B will then be moving in the direction indicated by the arrows X^3 and X^4 , respectively, while the piston C is stationary. Steam is entering the chamber of the piston A through the inlet 2^a , while the exhaust is being driven out through the port 1^a . In the chamber of the piston B the steam has been cut off by the action of the cam w , which has just passed and engaged the roller 2^r of the shaft 2^v and turned the valve V in the valve-box 1^b , thereby closing the inlet-port 1^b . The port 2^c of the piston C has just been opened by the action of the cam 2^w upon the roller r^s of the shaft v^4 and has become an exhaust-port, while the port 1^c will be opened by the cam 4^w engaging the roller 4^r . Steam will then enter through the port 1^c and act to drive the shaft in the direction indicated by the arrow X^5 ; but by this time the piston A will have moved until its vane has assumed a position about diametrically opposite to the abutment a' , when the cam 1^v , engaging with the roller r^s , will act to cut off the steam through the port 2^a and allow the expansion of the steam to further move the piston. By the time the steam has been cut off from the port 2^a of the piston A the piston B will have traveled to the point where the cam-arm t^s of the segmental gear T engages with the cam-arm 2^b of the main gear-wheel B' and drive the said piston the remaining distance or until its vane reaches the abutment. The relative position of the cam-arms t^s and 2^b at this point will correspond to the relative position of the cam-arms t^s and 2^g . (Best shown in Fig. 4.) The piston B in this position remains stationary until the cam-arm t^s of the segmental gear T' engages with the cam-arm 1^r of the auxiliary gear F', when it will begin to move in a direction opposite to the direction indicated by the arrow X^4 and steam will be admitted through the port 2^b by the action of the cam 2^w engaging the roller r^s upon the shaft v^3 in a manner similar to the action of the cam 2^w upon the roller r^s , attached to the shaft v^3 . The action in connection with all of the pistons and their gears is similar and occurs consecutively, and it will be seen that two of the pistons are at all times receiving the full action of the expansive steam. The port 1^a becomes an inlet-port shortly after the vane of the piston A has reached the abutment a' by the action of the cam 4^w engaging with the roller 4^r of the shaft 3^v after the cam 3^w has engaged with the roller 3^r to close the exhaust-port, and the port 2^a will then become an exhaust-port by the action of the cam 2^w engaging with the roller r^s of the shaft v^2 after the cam 1^w has cut off the steam by engaging with the roller r^s . When the piston B has completed its movement, the port 1^b becomes an exhaust-port by the action of the cam w^2 upon the roller 1^r of the shaft 2^v after the cam w has acted upon the roller 2^r to close the port and the port 2^b becomes an inlet-port through the action of the cam w^3 upon the roller r of the shaft v^3 after the cam w has engaged with the roller r^s to close the port 2^b . When the piston C has made its complete movement, the port 1^c will become an exhaust-port by the action of the cam w^2 engaging with the roller 1^r of the shaft 3^v after the cam w has engaged with the roller 2^r to cut off the steam. The port 1^c is closed at the proper time by the action of the cam 3^w engaging the roller 3^r of the shaft 3^v . The action of the cam and roller ends formed upon the various shafts is consecutive and similar for each complete oscillation of the pistons. The various cams all come into active operation with the proper roller ends at the proper time of each piston during each revolution of the driving-shaft S'. During the operation

of the engine the main gear-wheels A', B', and C' engage consecutively with the segmental gear T and act to drive the shaft in the direction indicated by the arrow X², while the 5 pistons move in an opposite direction. When the pistons move in the direction corresponding to the direction of the rotation of the shaft, the auxiliary gear-wheels operated by the secondary gear-wheels are adapted to engage consecutively with the auxiliary segmental gear, giving to the shaft the same rotary motion which is imparted to it by the main gear-wheel. While the main gear-wheel of the piston is engaging with the segmental gear, its adjacent 10 auxiliary gear does not engage with the auxiliary segmental gear, and while the auxiliary gear is engaging with the auxiliary segmental gear the main gear-wheels are not engaging with the segmental gear. The cam-arms are 15 provided to insure a positive action to the engaging gears, as well as to act as a guide for same and take away the strain from the teeth of the gears of the first impact. The cams all engage in a consecutive order, and all the 20 parts work together to give a continuous, even, and steady rotation to the driving-shaft.

It is obvious that I may employ upon my engine any of the approved governing devices for regulating the speed.

30 Various forms or methods of controlling the admission of steam into the chambers may be used in my device. I do not, therefore, wish to limit myself to the particular valve-controlling mechanism shown.

35 As hereinbefore stated, the engine illustrated in the drawings is particularly designed for use as a steam-engine; but it is obvious that by slight modifications my engine may be adapted so that numerous expandible fluids 40 may be used and the same operative result obtained, and I might also by adding the proper controlling mechanism adapt my engine to be used as an ignitable-gas engine.

Having thus described my invention, what 45 I claim as new, and desire to secure by Letters Patent, is—

1. In an engine, a shaft to be rotated, a plurality of piston-chambers grouped about said shaft, oscillating pistons in the respective 50 chambers, translating and commuting gearing between said pistons and shaft for converting the oscillating movements of the pistons into continuous rotary motion of the driven shaft in one direction, and mechanism controlling 55 the admission and exhaust of the fluid, substantially as described.

2. In an engine, a shaft to be rotated, a plurality of piston-chambers grouped concentrically about said shaft, oscillating pistons in the 60 respective chambers, translating and commuting gearing between said pistons and shaft for converting the movements of the pistons into continuous rotary motion of the shaft, and automatic mechanism controlling the admis-

sion of fluid successively to the said pistons 65 and its exhaust, substantially as described.

3. In an engine, a shaft to be rotated, a plurality of piston-chambers grouped about said shaft, oscillating pistons in the respective chambers, translating and commuting gearing 70 between said pistons and shaft for converting the movements of the pistons into continuous rotary motion of the shaft, and automatic valve mechanism controlling the admission of fluid successively to said pistons, its cut off 75 for use expansively, and its exhaust, substantially as described.

4. In an engine, a shaft to be rotated, three piston-chambers grouped concentrically about said shaft, oscillating pistons in the respective 80 chambers, translating and commuting gearing between said pistons and the driven shaft for converting the oscillatory movements of the pistons into continuous rotary motion of the shafts, and automatic valve mechanism controlling 85 the admission of fluid successively to said pistons, its cut off for use expansively, and its exhaust, substantially as described.

5. In an engine, a shaft to be rotated, a plurality of piston-chambers grouped adjacent to 90 said shaft, oscillating pistons in the respective chambers, translating and commuting gearing between the respective pistons and said shaft, and valve mechanism actuated by said shaft and controlling the admission of fluid to, and 95 its exhaust from said chambers, substantially as described.

6. In an engine, a shaft to be rotated, pistons adapted to oscillate in suitable chambers and grouped adjacent to the said shaft, means 100 for admitting a fluid under tension to the piston-chambers successively and exhausting it at proper times, and translating and commuting gearing between said pistons and shaft whereby the oscillating movements of the pistons 105 is converted into continuous rotary motion of the shaft, substantially as described.

7. In an engine, a shaft to be rotated, pistons adapted to oscillate in chambers grouped about said shaft, the oscillating axes of the 110 pistons being concentric and parallel with said shaft, automatic valve mechanism for admitting fluid to said pistons successively and for operating the exhaust therefrom, whereby the pistons shall be, at any given time, at different 115 points in their strokes, and translating and commuting gearing between said pistons and shaft for converting the oscillating movements of the pistons into continuous rotary motion of the shaft, substantially as described. 120

8. In an engine, a casing with piston-chambers having abutments formed therein, oscillating pistons adapted to oscillate within the 125 said piston-chambers, gear-wheels securely fastened to the shafts of the said oscillating pistons, a central shaft, mounted upon and passing through the said casing and a segmental gear securely fastened to the said cen-

tral shaft and adapted to engage with the aforesaid gear-wheels mounted upon the shafts of the said pistons; the said gear-wheels being adapted to engage with the said segmental gear while the pistons to which they are attached move in a direction opposite to the direction of the rotation of the said segmental gear and central shaft, substantially as described.

10. 9. In an engine, a casing with piston-chambers having abutments formed therein, oscillating pistons adapted to oscillate within the said piston-chambers, gear-wheels securely fastened to the shafts of the said oscillating pistons, duplicate gears securely fastened upon said shafts of the pistons, auxiliary shafts mounted upon the casing, auxiliary and duplicate gears securely fastened upon the said auxiliary shafts; the said duplicate gears upon being adapted to engage with the duplicate gears upon the said piston-shafts, a central shaft mounted upon and passing through the said casing and a segmental gear secured to the said shaft and adapted to engage with the aforesaid auxiliary gear-wheels mounted upon the said auxiliary shafts; the said auxiliary gear-wheels being adapted to engage with the said segmental gear while the piston moves in a direction corresponding to the direction of the rotation of the said segmental gear and central shaft, substantially as described.

10. 10. In an engine, a casing with piston-chambers having abutments formed therein, oscillating pistons adapted to oscillate within the said piston-chambers, gear-wheels securely fastened to the shafts of the said oscillating pistons, duplicate gears securely fastened upon the said shafts of the pistons, auxiliary shafts mounted upon the casing, auxiliary and duplicate gears mounted upon the said auxiliary shafts; the duplicate gears upon the said piston-shafts, a central shaft mounted upon and passing through the said casing, a segmental gear secured to the said shaft and adapted to engage with the aforesaid gear-wheels mounted upon the shafts of the pistons and an auxiliary segmental gear also secured to the said central shaft and adapted to engage with the aforesaid auxiliary gear-wheels mounted upon the said auxiliary shafts; the said segmental gear being revolved by means of the said auxiliary gear-wheels mounted upon the auxiliary shaft while the piston moves in a direction corresponding to the direction of the rotation of the said central shaft and segmental gears, substantially as described.

11. 11. In an engine, a casing with piston-chambers having abutments formed therein, oscillating pistons adapted to oscillate within the said piston-chambers, gear-wheels securely fastened to the shaft of the said oscillating pistons, cam projections formed upon the said

gear-wheels, a central shaft, mounted upon 65 and passing through the said casing, a segmental gear securely fastened to the said central shaft and adapted to engage with the aforesaid gear-wheels mounted upon the said shafts of the pistons, and cam projections formed 70 upon the said segmental gear and adapted to engage with the cam projections formed upon the aforesaid gear-wheels; the said gear-wheels being adapted to engage with the said segmental gear while the pistons to which they 75 are attached move in a direction opposite to the direction of the rotation of the said segmental gear and central shaft, substantially as described.

12. 12. In an engine, a casing with piston-chambers having abutments formed therein, oscillating pistons adapted to oscillate within the said piston-chambers, gear-wheels securely fastened to the shafts of the said oscillating pistons, duplicate gears securely fastened upon 80 the said shafts of the pistons, auxiliary shafts mounted upon the casing, auxiliary and duplicate gears securely fastened upon the said auxiliary shafts; the said duplicate gears being adapted to engage with the duplicate gears 85 upon the aforesaid piston-shafts, cam projections formed upon the said auxiliary gears, a central shaft mounted upon and passing through the said casing, a segmental gear secured to the said shaft and adapted to engage 90 with the aforesaid auxiliary gear-wheels fastened to the said auxiliary shafts, and cam projections formed upon the said segmental gear and adapted to engage with the cam projections formed upon the said auxiliary gears; 100 the said auxiliary gear-wheels being adapted to engage with the said segmental gear while the pistons move in a direction corresponding to the direction of the rotation of the segmental gear and central shaft, substantially 105 as described.

13. 13. In an engine, a casing with piston-chambers having abutments formed therein, oscillating pistons adapted to oscillate within the said piston-chambers, gear-wheels securely 110 fastened to the shafts of the said oscillating pistons, cam projections formed upon the said gear-wheels, duplicate gears securely fastened upon the said shafts of the pistons, auxiliary shafts mounted upon the casing, auxiliary and 115 duplicate gears mounted upon the said auxiliary shafts, cam projections formed upon the said auxiliary gears, a central shaft mounted upon and passing through the said casing, a segmental gear securely fastened to the said 120 shaft and adapted to engage with the aforesaid gear-wheels mounted upon the shafts of the pistons, cam projections formed upon the said segmental gear and adapted to engage with the cam projections formed upon the aforesaid gear-wheels, an auxiliary segmental gear also securely fastened to the said central shaft and adapted to engage with the afore-

6
said auxiliary gear-wheels mounted upon the said auxiliary shafts, and cam projections formed upon the said auxiliary segmental gear and adapted to engage with the cam projections formed upon the said auxiliary gears; the aforesaid duplicate gears upon the piston-shafts being adapted to engage with the duplicate gears of the aforesaid auxiliary shafts and the aforesaid gear-wheels being adapted 5 to engage with the aforesaid segmental gear to revolve the aforesaid central shaft when the pistons to which they are connected move in the direction opposite to the direction of the rotation of the said segmental gear and 10 central shaft, and the auxiliary gear-wheels being adapted to engage with the said auxiliary segmental gear to revolve the central shaft while the pistons are moving in a direction corresponding to the direction of the 15 rotation of the said central shaft and segmental gears, substantially as described.

14. In an engine, a casing with piston-chambers having abutments formed therein, oscillating pistons adapted to oscillate within the 20 said piston-chambers, gear-wheels securely fastened to the shafts of the said oscillating pistons, a central shaft mounted upon and passing through the said casing, a segmental gear securely fastened to the said central shaft and 25 adapted to engage with the aforesaid gear-wheels mounted upon the shafts of said pistons; the said gear-wheels being adapted to engage with the said segmental gear while the pistons to which they are attached move in a 30 direction opposite to the direction of the rotation of the said segmental gear and central shaft, inlet and exhaust ports formed in the aforesaid abutments in the piston-chambers, rotary valves mounted upon the casing and 35 suitably connected to the said inlet and exhaust ports and adapted to control the admission and exhaust of the expansible fluid through the said ports, contacting arms having roller ends, secured to the said rotary valves, and a cam-wheel mounted upon and rotating 40 with the aforesaid central shaft and provided with cam projections which are adapted to engage with the roller ends of the said contacting arms to open and close the inlet and exhaust ports leading to and from the piston-chambers, substantially as described.

15. In an engine, a casing with piston-chambers having abutments formed therein, oscillating pistons adapted to oscillate within the 45 said piston-chambers, gear-wheels securely fastened to the shafts of the said oscillating pistons, duplicate gears securely fastened upon the shafts of said pistons, auxiliary shafts mounted upon the casing, auxiliary and duplicate gears mounted upon the auxiliary shafts; the duplicate gears upon the auxiliary shaft being adapted to engage with the duplicate gears upon the piston-shafts, a central shaft 50 mounted upon and passing through the said casing, a segmental gear secured to the said central shaft and adapted to engage with the aforesaid gear-wheels mounted upon the shafts of the pistons, an auxiliary segmental gear also secured to the said central shaft and adapted to engage with the aforesaid auxiliary gear-wheels mounted upon the aforesaid piston-shafts while the pistons move in a direction 55 opposite to the direction of the rotation of the said segmental gear and central shaft, and the said auxiliary segmental gear being revolved by means of the said auxiliary gear-wheels mounted upon the auxiliary shafts while the piston moves in a direction corresponding to the direction of the rotation of the said central shaft and segmental gears, inlet and exhaust ports formed in the aforesaid abutments in the piston-chambers, rotary valves mounted upon the casing and suitably connected to the said inlet and exhaust ports and adapted 60 to control the admission and exhaust of the expansible fluid through the said ports, contacting arms having roller ends secured to the said rotary valve and a cam-wheel mounted upon and rotating with the aforesaid central shaft and provided with cam projections which are adapted to engage with the roller ends of the said contacting arms to open and

65 casing, a segmental gear secured to the said shaft and adapted to engage with the aforesaid auxiliary gear-wheels mounted upon the said auxiliary shafts; the said auxiliary gear-wheels being adapted to engage with the segmental gear while the piston moves in a direction 70 corresponding to the direction of the rotation of the said segmental gear and central shaft, inlet and exhaust ports formed in the aforesaid abutments in the piston-chambers, rotary valves mounted upon the casing and 75 suitably connected to the said inlet and exhaust ports and adapted to control the admission and exhaust of the expansible fluid through the said ports, contacting arms having roller ends, secured to the said rotary valves, and a cam-wheel mounted upon and rotating with the aforesaid central shaft and provided with cam projections which are adapted to engage with the roller ends of the said contacting arms to open and close the inlet and 80 exhaust ports leading to and from the piston-chambers, substantially as described.

16. In an engine, a casing with piston-chambers having abutments formed therein, oscillating pistons adapted to oscillate within the 85 said piston-chambers, gear-wheels securely fastened to the shafts of the said oscillating pistons, duplicate gears securely fastened upon the said shafts of the pistons, auxiliary shafts mounted upon the casing, auxiliary and duplicate gears mounted upon the auxiliary shafts; the duplicate gears upon the auxiliary shaft being adapted to engage with the duplicate gears upon the piston-shafts, a central shaft 90 mounted upon and passing through the said casing, a segmental gear secured to the said central shaft and adapted to engage with the aforesaid gear-wheels mounted upon the shafts of the pistons, an auxiliary segmental gear also secured to the said central shaft and adapted to engage with the aforesaid auxiliary gear-wheels mounted upon the aforesaid piston-shafts while the pistons move in a direction 95 opposite to the direction of the rotation of the said segmental gear and central shaft, and the said auxiliary segmental gear being revolved by means of the said auxiliary gear-wheels mounted upon the auxiliary shafts while the piston moves in a direction corresponding to the direction of the rotation of the said central shaft and segmental gears, inlet and exhaust ports formed in the aforesaid abutments in the piston-chambers, rotary valves mounted upon the casing and suitably connected to the said inlet and exhaust ports and adapted 100 to control the admission and exhaust of the expansible fluid through the said ports, contacting arms having roller ends secured to the said rotary valve and a cam-wheel mounted upon and rotating with the aforesaid central shaft and provided with cam projections which are adapted to engage with the roller ends of the said contacting arms to open and 105 close the inlet and exhaust ports leading to and from the piston-chambers, substantially as described.

17. In an engine, a casing with piston-chambers having abutments formed therein, oscillating pistons adapted to oscillate within the 110 said piston-chambers, gear-wheels securely fastened to the shafts of the said oscillating pistons, duplicate gears securely fastened upon the shafts of said pistons, auxiliary shafts mounted upon the casing, auxiliary and duplicate gears securely fastened upon the said auxiliary shafts; the said duplicate gears being adapted to engage with duplicate gears upon the said piston-shafts, a central shaft 115 mounted upon and passing through the said casing, a segmental gear secured to the said central shaft and adapted to engage with the aforesaid auxiliary gear-wheels mounted upon the auxiliary shafts while the piston moves in a direction corresponding to the direction of the rotation of the said central shaft and segmental gears, inlet and exhaust ports formed in the aforesaid abutments in the piston-chambers, rotary valves mounted upon the casing and suitably connected to the said inlet and exhaust ports and adapted 120 to control the admission and exhaust of the expansible fluid through the said ports, contacting arms having roller ends secured to the said rotary valve and a cam-wheel mounted upon and rotating with the aforesaid central shaft and provided with cam projections which are adapted to engage with the roller ends of the said contacting arms to open and 125 close the inlet and exhaust ports leading to and from the piston-chambers, substantially as described.

close the inlet and exhaust ports leading to and from the piston-chambers, substantially as described.

17. In an engine, a casing with piston-chambers having abutments formed therein, oscillating pistons adapted to oscillate within the said piston-chambers, gear-wheels securely fastened to the shafts of the said oscillating pistons, cam projections formed upon the said gear-wheels, a central shaft mounted upon and passing through the said casing, a segmental gear securely fastened to the said central shaft and adapted to engage with the aforesaid gear-wheels mounted upon the said shafts of the pistons, cam projections formed upon the said segmental gear and adapted to engage with the cam projections formed upon the aforesaid gear-wheels; the said gear-wheels being adapted to engage with the said segmental gear while the pistons to which they are attached move in a direction opposite to the rotation of the said segmental gear and central shaft, inlet and exhaust ports formed in the aforesaid abutments in the piston-chambers, rotary valves mounted upon the casing and suitably connected to the said inlet and exhaust ports and adapted to control the admission and exhaust of the expansible fluid through the said ports, contacting arms having roller ends secured to the said rotary valve, and a cam-wheel mounted upon and rotating with the aforesaid central shaft and provided with cam projections which are adapted to engage with the roller ends of the said contacting arms to open and close the inlet and exhaust ports leading to and from the piston-chambers, substantially as described.

18. In an engine, a casing with piston-chambers having abutments formed therein, oscillating pistons adapted to oscillate within the said piston-chambers, gear-wheels securely fastened to the shafts of the said oscillating pistons, duplicate gears securely fastened upon the said shafts of the oscillating pistons, auxiliary shafts mounted upon the casing, auxiliary and duplicate gears securely fastened upon the said auxiliary shafts; the said duplicate gears being adapted to engage with the duplicate gears upon the aforesaid piston-shafts, cam projections formed upon the said auxiliary gears, a central shaft mounted upon and passing through the said casing, a segmental gear secured to the said shaft and adapted to engage with the aforesaid auxiliary gear-wheels fastened to the said auxiliary shafts, cam projections formed upon the said segmental gear and adapted to engage with the cam projections formed upon the said auxiliary gears; the said auxiliary gear-wheels being adapted to engage with the said segmental gear while the pistons move in a direction corresponding to the direction of the rotation of the segmental gear and central shaft, inlet and exhaust ports formed in the aforesaid abutments in the piston-chambers, rotary valves mounted upon the casing and suitably connected to the said inlet and exhaust ports and adapted to control the admission and exhaust of the expansible fluid through the said ports, contacting arms having roller ends, secured to the said rotary valves, and a cam-wheel

ments in the piston-chambers, rotary valves 6 mounted upon the casing and suitably connected to the said inlet and exhaust ports and adapted to control the admission and exhaust of the expansible fluid through the said ports, contact-arms having roller ends, secured to 70 the said rotary valve, and a cam-wheel mounted upon and rotating with the aforesaid central shaft and provided with cam projections which are adapted to engage with the roller ends of the said contacting arms to open and 75 close the inlet and exhaust ports leading to and from the piston-chambers, substantially as described.

19. In an engine, a casing with piston-chambers having abutments formed therein, oscillating pistons adapted to oscillate within the said piston-chambers, gear-wheels securely fastened to the shafts of the said oscillating pistons, cam projections formed upon the said gear-wheels, duplicate gears securely fastened 85 upon the said shafts of the pistons, auxiliary shafts mounted upon the casing, auxiliary and duplicate gears mounted upon the said auxiliary shafts, cam projections formed upon the said auxiliary gears, a central shaft mounted 90 upon and passing through the said casing, a segmental gear fastened to the said shaft and adapted to engage with the aforesaid gear-wheels mounted upon the shafts of the pistons, cam projections formed upon the said segmental gear and adapted to engage with the cam projections formed upon the aforesaid gear-wheels, an auxiliary segmental gear also 95 securely fastened to the said central shaft and adapted to engage with the aforesaid auxiliary 100 gear-wheels mounted upon the auxiliary shafts, cam projections formed upon the said auxiliary segmental gear and adapted to engage with the cam projections formed upon the said auxiliary gear-wheels; the aforesaid duplicate 105 gears upon the piston-shafts being adapted to engage with the duplicate gears of the aforesaid auxiliary shafts and the aforesaid gear-wheels upon the piston-shafts being adapted 110 to engage with the aforesaid segmental gear to revolve the aforesaid central shaft when the pistons to which they are connected move in a direction opposite to the direction of the rotation of the segmental gear and central shaft, and the auxiliary gear-wheels being 115 adapted to engage with the auxiliary segmental gear to revolve the central shaft while the pistons are moving in a direction corresponding to the direction of the rotation of the said central shaft and segmental gears, inlet and 120 exhaust ports formed in the aforesaid abutments in the piston-chambers, rotary valves mounted upon the casing and suitably connected to the said inlet and exhaust ports and adapted to control the admission and exhaust 125 of the expansible fluid through the said ports, contacting arms having roller ends, secured to the said rotary valves, and a cam-wheel

mounted upon and rotating with the aforesaid central shaft and provided with cam projections which are adapted to engage with the roller ends of the said contacting arms to open 5 and close the inlet and exhaust ports leading to and from the piston-chambers, substantially as described.

20. In an engine, a casing with piston-chambers having abutments formed therein, oscillating pistons adapted to oscillate within the said piston-chambers, gear-wheels securely fastened to the shafts of the said oscillating pistons, a central shaft mounted upon and passing through the said casing, a segmental 10 gear securely fastened to the said central shaft and adapted to engage with the aforesaid gear-wheels mounted upon the shafts of the said pistons; the said gear-wheels being adapted to engage with the said segmental gear while 15 the pistons to which they are attached move in a direction opposite to the direction of the rotation of the said segmental gear and central shaft, inlet and exhaust ports formed in the aforesaid abutments in the piston-chambers, 20 rotary valves mounted upon the casing and suitably connected to the said inlet and exhaust ports and adapted to control the admission and exhaust of the expansible fluid through the said ports and suitable means for operating 25 the said valves, substantially as described.

21. In an engine, a casing with piston-chambers having abutments formed therein, oscillating pistons adapted to oscillate within the said piston-chambers, gear-wheels securely 30 fastened to the shafts of the said oscillating pistons, duplicate gears securely fastened upon the shafts of the said pistons, auxiliary shafts mounted upon the casing, auxiliary and duplicate gears securely fastened upon the said 35 auxiliary shafts; the said duplicate gears being adapted to engage with duplicate gears upon the said piston-shafts, a central shaft mounted upon and passing through the said casing, a segmental gear secured to the said 40 shaft and adapted to engage with the aforesaid auxiliary gear-wheels mounted upon the said auxiliary shaft; the said auxiliary gear-wheels being adapted to engage with a segmental gear while the piston moves in a direction 45 corresponding to the direction of the rotation of the said segmental gear and central shaft, inlet and exhaust ports formed in the aforesaid abutments in the piston-chambers, rotary valves mounted upon the casing 50 and suitably connected to the said inlet and exhaust ports and adapted to control the admission and exhaust of the expansible fluid through the said ports, and suitable means for operating the said valves, substantially as described.

22. In an engine, a casing with piston-chambers having abutments formed therein, oscillating pistons adapted to oscillate within the said piston-chambers, gear-wheels securely 55 fastened to the shafts of the said oscillating

pistons, duplicate gears securely fastened upon the said shafts of the pistons, auxiliary shafts mounted upon the casing, auxiliary duplicate gears mounted upon the said auxiliary shafts; the duplicate gears upon the auxiliary shafts 70 being adapted to engage with the duplicate gears upon the piston-shafts, a central shaft mounted upon and passing through the said casing, a segmental gear secured to said central shaft and adapted to engage with the aforesaid gear-wheels mounted upon the shafts of the pistons, and an auxiliary segmental gear also securely fastened to said central shaft and adapted to engage with the aforesaid auxiliary gear-wheels mounted upon the aforesaid piston-shafts while the pistons move in a direction 75 opposite to the direction of the rotation of the said segmental gear and central shaft, the said auxiliary segmental gear being revolved by means of the said auxiliary gear-wheels mounted upon the auxiliary shafts while the piston moves in a direction corresponding to the direction of the rotation of the said central shaft and segmental gears, inlet and exhaust ports formed in the aforesaid abutments in the piston-chambers, rotary valves mounted upon the casing and suitably connected to the said inlet and exhaust ports and adapted to control the admission and exhaust of the expansible 80 fluid through the said ports, and suitable means for operating the said valves, substantially as described.

23. In an engine, a casing with piston-chambers having abutments formed therein, oscillating pistons adapted to oscillate within the said piston-chambers, gear-wheels securely fastened to the shafts of the said oscillating pistons, cam projections formed upon the said gear-wheels, a central shaft mounted upon and passing through the said casing, a segmental gear 85 securely fastened to the said central shaft and adapted to engage with the aforesaid gear-wheels mounted upon the said shafts of the pistons, cam projections formed upon the said segmental gear and adapted to engage with the cam projections formed upon the aforesaid gear-wheels; the said gear-wheels being adapted to engage with the said segmental gear while the pistons to which they are attached move in a direction opposite to the rotation 90 of the said segmental gear and central shaft, inlet and exhaust ports formed in the aforesaid abutments in the piston-chambers, rotary valves mounted upon the casing and suitably connected to the said inlet and exhaust ports and adapted to control the admission and exhaust of the expansible fluid through the said ports, and suitable means for operating the said valves, substantially as described.

24. In an engine, a casing with piston-chambers having abutments formed therein, oscillating pistons adapted to oscillate within the said piston-chambers, gear-wheels securely fastened to the shafts of the said oscillating pistons, duplicate gears securely fastened upon 95

the said shafts of the oscillating pistons, auxiliary shafts mounted upon the casing, auxiliary and duplicate gears securely fastened upon the said auxiliary shafts; the said duplicate gears upon the auxiliary shafts being adapted to engage with the duplicate gears upon the aforesaid piston-shafts, cam projections formed upon the said auxiliary gears, a central shaft mounted upon and passing through the said casing, a segmental gear secured to the said shafts and adapted to engage with the aforesaid auxiliary gear-wheels fastened to the said auxiliary shafts, cam projections formed upon the said segmental gear and adapted to engage with the cam projections formed upon the said auxiliary gear-wheels; the said auxiliary gear-wheels being adapted to engage with the said segmental gear while the pistons move in a direction corresponding to the direction of the rotation of the said central shaft and segmental gears, inlet and exhaust ports formed in the aforesaid abutments in the piston-chambers, rotary valves mounted upon the casing and suitably connected to the said inlet and exhaust ports and adapted to control the admission and exhaust of the expansible fluid through the said ports, and suitable means for operating the said valves, substantially as described.

26. In an engine, a casing with piston-chambers having abutments formed therein, oscillating pistons adapted to oscillate within the said piston-chambers, gear-wheels securely fastened to the shafts of the said oscillating pistons, a central shaft mounted upon and passing through the said casing, a segmental gear securely fastened to the said central shaft and adapted to engage with the aforesaid gear-wheels mounted upon the shafts of the said pistons; the said gear-wheels being adapted to engage with the said segmental gear while the pistons to which they are attached move in a direction opposite to the direction of the rotation of the said segmental gear and central shaft, inlet and exhaust ports formed in the aforesaid abutments in the piston-chambers, rotary valves mounted upon the casing and suitably connected to the said inlet and exhaust ports and adapted to control the admission and exhaust of the expansible fluid through the said ports, suitable operating mechanism for opening and closing the ports at the proper time and suitable means for governing the admission of the expansible fluid to regulate the speed of the engine, substantially as described.

27. In an engine, a casing with piston-chambers having abutments formed therein, oscillating pistons adapted to oscillate within the said piston-chambers, gear-wheels securely fastened to the shaft of the said oscillating pistons, duplicate gears securely fastened upon the shafts of the said pistons, auxiliary shafts mounted upon the casing, auxiliary and duplicate gears mounted upon the said auxiliary shafts, cam projections formed upon the said auxiliary gears, a central shaft mounted upon and passing through the said casing, a segmental gear fastened to the said shaft and adapted to engage with the aforesaid gear-wheels mounted upon the auxiliary shafts, cam projections formed upon the said auxiliary segmental gear and adapted to engage with the cam projections formed upon the said auxiliary gear-wheels, an auxiliary segmental gear also securely fastened to the said central shaft and adapted to engage with the aforesaid auxiliary gear-wheels mounted upon the auxiliary shafts, cam projections formed upon the said auxiliary segmental gear and adapted to engage with the cam projections formed upon the said auxiliary gear-wheels; the aforesaid duplicate gears upon the piston-shafts being adapted to engage with the duplicate gears of the aforesaid auxiliary shafts and the aforesaid gear-wheels upon the piston-shafts being adapted to engage with the aforesaid segmental gear to revolve the aforesaid central shaft when the pistons to which they are connected move in a direction opposite to the direction of the rotation of the segmental gear and central shaft,

connected to the said inlet and exhaust ports and adapted to control the admission and exhaust of the expansible fluid through the said ports, suitable operating mechanism for opening and closing the ports at the proper time and suitable means for governing the admission of the expansible fluid to regulate the speed of the engine, substantially as described.

28. In an engine, a casing with piston-chambers having abutments formed therein, oscillating pistons adapted to oscillate within the said piston-chambers, gear-wheels securely fastened to the shafts of the said oscillating pistons, duplicate gears securely fastened upon the said shafts of the pistons, auxiliary shafts mounted upon the casing, auxiliary and duplicate gears mounted upon the said auxiliary shafts; the duplicate gears upon the auxiliary shafts being adapted to engage with the duplicate gears upon the piston-shafts, a central shaft mounted upon and passing through the said casing, a segmental gear secured to the said central shaft and adapted to engage with the aforesaid gear-wheels mounted upon the shafts of the pistons, an auxiliary segmental gear also secured to the central shaft and adapted to engage with the aforesaid auxiliary gear-wheels mounted upon the aforesaid piston-shafts, while the pistons move in the direction opposite to the direction of the rotation of the said segmental gear and central shaft, and the said auxiliary segmental gear being revolved by means of the said auxiliary gear-wheel mounted upon the auxiliary shaft while the piston moves in the direction corresponding to the direction of the rotation of the central shaft and segmental gear, inlet and exhaust ports formed in the aforesaid abutments in the piston-chambers, rotary valves mounted upon the casing and suitably connected to the said inlet and exhaust ports and adapted to control the admission and exhaust of the expansible fluid through the said ports, suitable operating mechanism for opening and closing the ports at the proper time, and suitable means for governing the admission of the expansible fluid to regulate the speed of the engine, substantially as described.

29. In an engine, a casing and piston-chambers having abutments formed therein, oscillating pistons adapted to oscillate within the said piston-chambers, gear-wheels securely fastened to the shafts of the said oscillating pistons, cam projections formed upon the said gear-wheels, a central shaft mounted upon and passing through the said casing, a segmental gear securely fastened to the said central shaft and adapted to engage with the aforesaid gear-wheels mounted upon the said shafts of the pistons, cam projections formed upon the said segmental gear and adapted to engage with the cam projections formed upon the aforesaid gear-wheels; the said gear-wheels being adapted to engage with the said segmental gear while the pistons to which they are attached

move in a direction opposite to the rotation of the said segmental gear and central shaft, inlet and exhaust ports formed in the aforesaid abutments in the piston-chambers, rotary valves mounted upon the casing and suitably connected to the said inlet and exhaust ports and adapted to control the admission and exhaust of the expansible fluid through the said ports, suitable operating mechanism for opening and closing the ports at the proper time, and suitable means for governing the admission of the expansible fluid to regulate the speed of the engine, substantially as described.

30. In an engine, a casing with piston-chambers having abutments formed therein, oscillating pistons adapted to oscillate within the said piston-chambers, gear-wheels securely fastened to the shafts of said oscillating pistons, duplicate gears suitably fastened upon the shafts of the said oscillating pistons, auxiliary shafts mounted upon the casing, auxiliary duplicate gears securely fastened upon the said auxiliary shafts; the said duplicate gears being adapted to engage with the duplicate gears upon the aforesaid piston-shafts, cam projections formed upon the said auxiliary gears, a central shaft mounted upon and passing through the said casing, a segmental gear secured to the said shaft and adapted to engage with the aforesaid auxiliary gear-wheels fastened to the auxiliary shafts, cam projections formed upon the said segmental gear and adapted to engage with the cam projections formed upon the said auxiliary gears; the said auxiliary gears being adapted to engage with the said segmental gear while the pistons move in a direction corresponding to the direction of the rotation of the said segmental gear and central shaft, inlet and exhaust ports formed in the aforesaid abutments in the piston-chambers, rotary valves mounted upon the casing and suitably connected to the said inlet and exhaust ports and adapted to control the admission and exhaust of the expansible fluid through the said ports, suitable operating mechanism for opening and closing the ports at the proper time, and suitable means for governing the admission of the expansible fluid to regulate the speed of the engine, substantially as described.

31. In an engine, a casing with piston-chambers having abutments formed therein, oscillating pistons adapted to oscillate within the said piston-chambers, gear-wheels securely fastened to the shafts of the said oscillating pistons, cam projections formed upon the said gear-wheels, duplicate gears securely fastened upon the said shafts of the pistons, auxiliary shafts mounted upon the casing, auxiliary and duplicate gears mounted upon the said auxiliary shafts, cam projections formed upon the said auxiliary gears, a central shaft mounted upon and passing through the said casing, a segmental gear fastened to the said shaft and adapted to engage the aforesaid gear-wheels.

mounted upon the shafts of the pistons, cam projections formed upon the said segmental gear and adapted to engage with the cam projections formed upon the aforesaid gear-wheels, an auxiliary segmental gear also securely fastened to the said central shaft and adapted to engage with the aforesaid auxiliary gear-wheels mounted upon the auxiliary shafts, cam projections formed upon the said auxiliary segmental gear and adapted to engage with the cam projections formed upon the said auxiliary gear-wheels; the aforesaid duplicate gears upon the piston-shafts being adapted to engage with the duplicate gears of the aforesaid auxiliary shafts and the aforesaid gear-wheels upon the piston-shafts being adapted to engage with the aforesaid segmental gear to revolve the aforesaid central shaft when the pistons to which they are connected move in a direction opposite to the direction of the rotation of the segmental gear and central shaft, and the auxiliary gear-wheels being adapted to engage in the auxiliary segmental gear to revolve the central shaft while the pistons are moving in a direction corresponding to the direction of the rotation of the said central shaft and segmental gears, inlet and exhaust ports formed in the aforesaid abutments in the piston-chambers, rotary valves mounted upon the casing and suitably connected to the said inlet and exhaust ports and adapted to control the admission and exhaust of expansible fluid through the said ports, suitable operating mechanism for opening and closing the ports at the proper time, and suitable means for governing the admission of the expansible fluid to regulate the speed of the engine, substantially as described.

32. In an engine, a casing with piston-chambers having abutments formed therein, oscillating pistons adapted to oscillate within the said piston-chambers, gear-wheels securely fastened to the shafts of the said oscillating pistons, a central shaft mounted upon and passing through the said casing, a segmental gear securely fastened to the said central shaft and adapted to engage with the aforesaid gear-wheels mounted upon the shafts of the said pistons; the said wheels being adapted to engage with the said segmental gear while the pistons to which they are attached move in a direction opposite to the direction of the rotation of the said segmental gear and central shaft, and suitable packing for the said oscillating pistons, substantially as described.

33. In an engine, a casing with piston-chambers having abutments formed therein, an oscillating piston adapted to oscillate within the said piston-chambers, gear-wheels securely fastened to the shafts of the said oscillating pistons, duplicate gears securely fastened upon the said shafts and the pistons, auxiliary shafts mounted upon the casing, auxiliary and duplicate gears securely fastened upon the said auxiliary shafts; the said duplicate gears being

adapted to engage with the duplicate gears upon the said piston-shafts, a central shaft mounted upon and passing through the said casing, and a segmental gear secured to the said shaft and adapted to engage in the aforesaid auxiliary gear-wheels mounted upon the said auxiliary shafts, the said auxiliary gear-wheels being adapted to engage with the said segmental gear while the piston moves in a direction corresponding to the direction of the rotation of the said segmental gear and central shaft, and suitable packing for said oscillating pistons, substantially as described.

34. In an engine, a casing with piston-chambers having abutments formed therein, oscillating pistons adapted to oscillate within the said piston-chambers, gear-wheels securely fastened to the shafts of the said oscillating pistons, duplicate gears securely fastened upon the said shafts of the oscillating pistons, auxiliary shafts mounted upon the casing, auxiliary and duplicate gears mounted upon the said auxiliary shafts; the duplicate gears upon the auxiliary shafts being adapted to engage with the duplicate gears upon the said piston-shafts, a central shaft mounted upon and passing through the said casing, a segmental gear secured to the said shaft and adapted to engage with the aforesaid gear-wheels mounted upon the shafts of the pistons, an auxiliary segmental gear also secured to the said central shaft and adapted to engage with the aforesaid auxiliary gear-wheels mounted upon the said auxiliary shafts; the said segmental gear being revolved by means of the aforesaid segmental gear-wheels mounted upon the aforesaid piston-shafts while the piston moves in the direction opposite to the direction of the rotation of the said segmental gear and shaft, and the said auxiliary segmental gear being revolved by means of the said auxiliary gear-wheel mounted upon the auxiliary shaft while the piston moves in the direction corresponding to the direction of the rotation of the said central shaft and segmental gears, and suitable packing for the said oscillating pistons, substantially as described.

35. In an engine, a casing with piston-chambers having abutments formed therein, oscillating pistons adapted to oscillate within the said piston-chambers, gear-wheels securely fastened to the shafts of the said oscillating pistons, cam projections formed upon the said gear-wheels, a central shaft mounted upon and passing through the said casing, a segmental gear securely fastened to the said central shaft and adapted to engage in the aforesaid gear-wheels mounted upon the said shafts of the pistons, cam projections formed upon the said segmental gear and adapted to engage with the cam projections formed upon the aforesaid gear-wheels; the said gear-wheels being adapted to engage with the said segmental gear while the pistons to which they are attached move in a direction opposite to

the direction of the rotation of the said segmental gear and central shaft, and suitable packing for the said oscillating pistons, substantially as described.

- 5 36. In an engine, a casing with piston-chambers having abutments formed therein, oscillating pistons adapted to oscillate within the said piston-chambers, gear-wheels securely fastened to the shafts of the said oscillating 10 pistons, duplicate gears securely fastened upon the said shafts of the pistons, auxiliary shafts mounted upon the casing, auxiliary and duplicate gears securely fastened upon the said auxiliary shafts; the said duplicate gears being adapted to engage with the duplicate gears upon the aforesaid piston-shafts, cam projections formed upon the said auxiliary gears, a central shaft mounted upon and passing through the casing, a segmental gear secured 15 to the said shaft and adapted to engage in the aforesaid auxiliary gear-wheels and fastened to the said auxiliary shafts, cam projections formed upon the said segmental gear and adapted to engage with the cam projections 20 formed upon the said auxiliary gears; the said auxiliary gear-wheels being adapted to engage with the said segmental gear while the pistons move in a direction corresponding to the direction of the rotation of the segmental gear 25 and central shaft, and suitable packing for the said oscillating pistons, substantially as described.

- 30 37. In an engine, a casing with piston-chambers having abutments formed therein, oscillating pistons adapted to oscillate within the said piston-chambers, gear-wheels securely fastened to the said oscillating pistons, cam projections formed upon the said gear-wheels, duplicate gears securely fastened upon the said 35 shafts of the pistons, auxiliary shafts mounted upon the casing, auxiliary and duplicate gears mounted upon the said auxiliary shafts, cam 40

projections formed upon the said auxiliary gears, a central shaft mounted upon and passing through the said casing, a segmental gear 45 securely fastened to the said shafts and adapted to engage with the aforesaid gear-wheels mounted upon the shafts of the pistons, cam projections formed upon the said segmental gears and adapted to engage with the cam projections 50 formed upon the aforesaid gear-wheels, an auxiliary segmental gear also securely fastened to the said central shaft and adapted to engage with the aforesaid auxiliary gear-wheels mounted upon the said auxiliary shafts, cam projections formed upon the said auxiliary segmental gears and adapted to engage with the cam projections formed upon the said auxiliary gears; the aforesaid duplicate gears upon the piston-shafts being adapted 55 to engage with the duplicate gears of the aforesaid auxiliary shafts and the aforesaid gear-wheels being adapted to engage with the aforesaid segmental gear to revolve the central shaft when the pistons to which they are 60 connected move in the direction opposite to the direction of the rotation of the said segmental gear and central shaft, and the auxiliary gear-wheels being adapted to engage with the said auxiliary segmental gear to revolve 65 the central shaft while the pistons are moving in a direction corresponding to the direction of the rotation of the central shaft and segmental gears, and suitable packing for the 70 said oscillating pistons, substantially as described.

In testimony that I claim the foregoing as my invention I have signed my name, in presence of two witnesses, this 1st day of July, 1901.

FRANK H. LINDNER.
